HANGER FOR ELECTRICAL LIGHTING
FIXTURES

Arthur I. Appleton, Evanston, Ill., assignor to Appleton Electric Company, Chicago, Ill., a corporation of Illinois

Application February 15, 1947, Serial No. 728,808

13 Claims. (Cl. 248—343)

1

The present invention pertains to a support for electrical lighting fixtures and more particularly to a hanger whereby such fixtures may be safely supported directly from a conventional outlet box through the medium of fastening screws threaded into mounting lugs extending inwardly from the walls of the box. It sometimes happens that the threaded portions of either the screws or the box lugs are imperfectly manufactured, or in making fixture installations such threaded portions become stripped or otherwise damaged. Also, the screws may not be securely tightened so that over a period of time ordinary building vibration can cause the screws to work loose. Thus fixtures supported by the use of such lugs are apt to become detached and fall.

Generally stated, it is an object of the invention to overcome the aforementioned difficulties in the provision of a novel hanger for use with a conventional outlet box that is simple and sturdy in construction, and inexpensive to manufacture.

More particularly, it is an object to provide an improved fixture hanger which is adapted for use with conventional outlet boxes and which includes a safety catch means engageable with the lugs on an outlet box upon failure or removal of the mounting screws so that the fixture is prevented from falling.

The objects of the invention thus generally set forth, together with other and ancillary advantages are attained by the construction and arrangement shown by way of illustration in the accompanying drawings, in which:

Figure 1 is a bottom plan view of a hanger embodying the present invention, the same being shown applied to a conventional outlet box.

Fig. 2 is a top fragmentary perspective view of the catch means of the hanger.

Fig. 3 is an enlarged fragmentary plan view partly in section of the hanger in installed position relative to the outlet box.

Fig. 4 is a sectional view taken substantially in the plane of line 4—4 of Fig. 1.

Fig. 5 is a sectional view taken substantially in the plane of line 5—5 of Fig. 3.

Fig. 6 is similar to Fig. 5 but showing the relation of the components with the mounting screw removed.

Fig. 7 is a perspective view similar to Fig. 2 but illustrating a modified form of the invention.

2

Fig. 8 is a fragmentary elevation showing component relationship when the hanger is installed under normal conditions.

Fig. 9 is similar to Fig. 8 but showing the position of the components when the mounting screw has been removed.

While the invention is susceptible of various modifications and alternative constructions, there is shown in the drawings and will herein be described in detail preferred embodiments, but it is to be understood that it is not thereby intended to limit the invention to the specific forms disclosed, but it is intended to cover all modifications and alternative constructions falling within the spirit and scope of the invention as expressed in the appended claims.

By way of illustration a hanger embodying the instant invention is shown in Figure 1 applied to a conventional, generally octagonal outlet box 10. As is customary, the latter has a pair of mounting lugs 12 extending inwardly from the outer edges of a pair of opposite walls 14 of the box. Each lug is drilled and screw-threaded to receive a fixture mounting screw 16.

The improved hanger comprises, in general, a fixture supporting member herein shown as a substantially circular plate 20 serving also as a cover for the outlet box 10, and embodies safety catch means generally designated 30 for coaction with the mounting lugs 12 on the outlet box upon failure of the mounting screws 16.

As shown, the plate member 20 has a plurality of curved peripheral slots 21 for engagement by appropriate parts on the fixture itself, and secured to the plate centrally thereof is an electrical plug receptacle 23. Provision is also made at 24 to receive the switch for this socket.

So that the hanger can be secured to the outlet box by means of conventional mounting screws, outwardly from the center of the plate in position to receive such screws are a pair of diametrically positioned key-hole slots 25, the enlarged portions 26 of which are of such size as to allow unobstructed passage of the head of the mounting screw 16 therethrough upon installation of the hanger. The narrow portions 27 of these slots are of such size that the edges thereof underlie the heads of the screws when the hanger is installed.

The safety catch means 30 of the hanger for

coaction with the box lugs 12 upon the failure of the screws 16 to hold the fixture in place, are positioned on the upper surface of the plate 20. In the drawings, two of these safety catches are illustrated, one adjacent each of the slots 25. Each safety catch comprises an anchor member or rib 31 rigid with the plate 20 in substantially perpendicular relation thereto, and a laterally extending member or flange 32 disposed in overlying and vertically spaced relation to the hanger plate and forming a stop shoulder for engagement with the box lug should the fixture and hanger drop downwardly under the force of gravity. Preferably the rib 31 is formed separately from the plate and is fixed thereto in any suitable manner such as by the use of a pair of headed-over studs 33 extending through holes provided therefor in the plate. The stop shoulder 32 is integrally formed with the rib 31 and its free edge terminates immediately over the inner edge of the narrow portion 27 of the slot 25. Thus, should a long mounting screw be used, it will be unhindered by the stop shoulder.

Means is provided to prevent rotational movement of the hanger relative to the box lugs when the lugs and stop shoulders are in engagement. In the form illustrated in Figs. 1 through 5 inclusive, the means employed comprises the formation of the rib 31 in arcuate shape so that one end thereof extends along the bottom of the slot portion 27. The other end of the rib is fashioned into a bendable finger 34 which is detached from the plate 20 and which extends along the enlarged slot portion 26. So that access may be had to the finger 34 from the opposite side of the plate 20 an aperture 35 is provided in the plate through which a tool can be passed in order to bend the finger into a position to engage the side of the lug 12. To afford additional purchase for the inserted tool the finger 34 is provided with an offset portion adjacent its end and overlying the access aperture 35. Thus limiting abutments are provided on opposite sides of the lugs 12 preventing any relative rotational movement between the hanger and the lugs.

In the form of the invention shown in Figs. 7, 8 and 9, the rib 31 extends along the slot portion 27 and its flange 32 is provided with limiting abutments for engagement with the sides of the lug 12 which are rendered effective upon falling movement of the hanger to prevent any relative rotational movement between the hanger and the box and to retain the catch and lug in engagement. As shown, the flange has downwardly bent portions or tabs 36 constituting such abutments. These downwardly extending tabs 36 terminate a sufficient distance above the plate 20 to allow clearance for the passage of the lug 12. Thus when the stop shoulder rests upon the lug, the former is held against rotational movement by the tabs 36 engaging with the opposite edges of the lug. These tabs are permanently set in position and no bending thereof is required as was the case in the first form illustrated. Thus there is no necessity for access thereto from the opposite side of the plate 20.

To install the hanger illustrated in Figs. 1 through 5 on the outlet box 10, the mounting screws 16 are loosely threaded into the holes in the mounting lugs 12 and the hanger is positioned so that upon raising it toward the box the screw heads will pass through the enlarged slot portions 26 and at the same time the mounting lugs 12 will pass through the space between the shoulders 32 and the fingers 34 of the safety

catches 30. The hanger is then rotated slightly to position the bodies of the screws in the narrow slot portions 27. In this position the shoulders 32 overlie the lugs 12 of the box 10 as best shown in Fig. 4. The screws 16 are then tightened to secure the fixture in place. A screwdriver or some similar tool is then inserted through the access aperture 35, and using the side thereof as a fulcrum, the finger 34 is bent to a position overlying the enlarged slot portions 26. Thus the lug is prevented from rotational movement into such position that the heads of the screws could pass through the enlarged slot portions or the lugs move from position beneath the stop shoulders 32.

The installation of the form of fixture hanger illustrated in Figs. 7, 8 and 9, is accomplished in much the same manner as hereinbefore described. With the mounting screws 16 loosely threaded into the lugs 12, the hanger is moved so that the screw heads pass through the enlarged slot portions 27; such movement is continued until the spaces between the tabs 36 and the plate 20 are opposite the lugs 12. The hanger is then rotated so that the shoulders 32 of the catches overlie the lugs 12 in such position as shown in Fig. 8. Then should the hanger drop downwardly, the shoulders 32 will engage the lugs 12 in such position that the lugs will be retained between the tabs 36 as shown in Fig. 9. Further, this construction permits the hanger to be readily removed, if it be so desired. By merely lifting the hanger to position the space between the tab 36 and the plate 20 opposite the lug 12 the hanger can be rotated and the lug will be freed from engagement by the catch.

With the fixture hanging means heretofore employed should the mounting screw threads be stripped or the screws accidentally become removed the fixture would fall; however, utilization of a hanger constructed in accordance with the present invention including safety catch means for engagement with the box lugs will prevent such falling as would normally occur.

I claim as my invention:

1. A hanger for mounting a fixture on an outlet box having a lug thereon and fastening means coacting with said lug, said hanger comprising, in combination, a plate adapted to support said fixture and cover said box, and safety catch means rigidly secured to said plate and adapted to engage said lug upon failure of said fastening means to prevent complete dislocation of said fixture and hanger.

2. A hanger for mounting a fixture on an outlet box having a lug thereon adapted to receive a mounting screw, said hanger comprising, in combination, a plate to support said fixture and having a slot therein with a narrow portion for the reception of the screw shank and an enlarged portion permitting passage of the screw head, catch means rigid with said plate and adapted to engage said lug to prevent complete dislocation of said hanger, and means for engagement with said lug to prevent rotation of said hanger relative to said box and shifting of said screw from the narrow portion of said slot into the enlarged portion thereof.

3. A hanger for mounting a fixture on an outlet box having a lug thereon adapted to receive a mounting screw, said hanger comprising, in combination, a plate to support said fixture and having a slot therein with a narrow portion for the reception of the screw shank and an enlarged portion permitting passage of the screw head, and means rigid with said plate and adapted to

engage said lug to prevent rotation of said hanger relative to said box and shifting of said screw from the narrow portion of said slot into the enlarged portion thereof.

4. In a hanger for an electric fixture and for use with a conventional outlet box having a lug thereon and fastening means coacting with said lug, the combination of a plate having a slot to accommodate said fastening means and an excess aperture therein with safety catch means including a rib secured to said plate adjacent said slot and extending upwardly therefrom, a bendable finger extending from said body portion along said slot, and a stop shoulder projecting from said body, overlying said plate in spaced relation thereto and spaced from said finger so that said lug can pass therebetween upon installation of the hanger, said finger being accessible through said aperture so that it can be bent into a position over said slot, said safety catch means being adapted to engage said lug upon failure of said fastening means and said finger forming an abutment for said lug for retaining said catch means and said lug in engagement to prevent said hanger and said fixture from falling.

5. A hanger for an electrical fixture and for use with a conventional outlet box having a lug thereon adapted to receive a mounting screw, said hanger comprising, in combination, a plate to cover said box and support said fixture and having a slot formed therein to permit passage of the head of said mounting screw and upon slight rotation of said plate to grip the screw, and catch means including a rib secured to said plate adjacent said slot and having one end thereof terminating in a finger extending toward said slot, and a shoulder portion extending from said body portion in overlying relation to said plate and spaced from said finger so that said box lug can pass therebetween upon installation of the hanger, said finger being bendable to a position over said slot to form an abutment for said lug to prevent shifting of said hanger into dislocating position upon accidental loosening of said screw.

6. A hanger for an electrical fixture and for use with a conventional outlet box having a lug thereon adapted to receive a mounting screw, said hanger comprising, in combination, a plate to cover said box and support said fixture and having a slot therein to accommodate said mounting screw, and catch means secured to said plate and including a stop member rigid with and spaced upwardly from the plate to permit passage of said box lug therebetween upon installation of said hanger, said catch means being adapted to engage said lug upon failure of said screw.

7. A hanger for an electrical fixture and for use with a conventional outlet box having a lug thereon adapted to receive a mounting screw, said hanger comprising, in combination, a plate to cover said box and support said fixture and having a slot therein to accommodate said mounting screw, and catch means secured to said plate and including a rib extending upwardly from the plate, a stop shoulder extending laterally from said rib and overlying said plate and a tab extending downwardly from said shoulder toward said plate but having its end spaced therefrom to permit passage of said box lug therebetween upon installation of said hanger, said shoulder being adapted to engage said lug upon failure of said screw, and said tab forming a limiting abutment for retaining said shoulder and said lug in engagement.

8. A hanger for an electrical fixture and for

use with a conventional outlet box having a lug thereon adapted to receive a mounting screw, said hanger comprising, in combination, a plate to cover said box and support said fixture and having a slot therein with a narrow portion for the reception of the screw shank and an enlarged portion permitting passage of the screw head, and a safety catch adjacent said slot including a member spaced from and overlying said plate for engagement with said lug upon disengagement of the mounting screw and having limiting abutments thereon for engagement with the opposite side edges of the lug to prevent rotational movement of the plate relative to the box and shifting of said screw from the narrow portion of said slot into the enlarged portion thereof.

9. A hanger for an electrical fixture and for use with a conventional outlet box having a lug thereon adapted to receive a mounting screw, said hanger comprising, in combination, a plate to cover said box and support said fixture and having a slot therein with a narrow portion for the reception of the screw shank and an enlarged portion permitting passage of the screw head, and a safety catch adjacent said slot including a member spaced from and overlying said plate for engagement with said lug upon disengagement of said screw fixture and having limiting abutments thereon for engagement with the opposite side edges of the lug to prevent rotational movement of the plate and shifting of said screw from the narrow portion of said slot into the enlarged portion thereof, at least one of said abutments terminating above said plate to permit passage of said lug therebetween upon installation or removal of the hanger.

10. A hanger for an electrical fixture and for use with a conventional outlet box having lugs thereon adapted to receive mounting screws, said hanger comprising, in combination, a plate to cover said box and support said fixture and having slots therein to accommodate said mounting screws, two safety catches secured to said plate each of which includes a rib extending upwardly from the plate, a flange extending laterally from said rib and overlying said plate and having its ends turned downwardly toward said plate, one of said ends terminating above said plate to permit passage of said lug therebetween upon installation of the hanger, said flange being adapted to engage said lug upon failure of said screw, and said downturned ends forming limiting abutments for retaining said flange and said lug in engagement and preventing relative rotational movement.

11. A hanger for mounting a fixture on an outlet box having lugs thereon adapted to receive mounting screws, said hanger comprising, in combination, a plate to support said fixture having slots therein each of which has a narrow portion for the reception of a screw shank and an enlarged portion permitting passage of a screw head and a safety catch adjacent each of said slots and adapted to engage said lugs to prevent complete dislocation of said hanger, said safety catches including means for engagement with said lugs to prevent rotation of said hanger relative to said box and shifting of said screws from the narrow slot portions into the enlarged slot portions.

12. A hanger for mounting a fixture on an outlet box having a lug thereon adapted to receive a mounting screw, said hanger comprising, in combination, a fixture supporting member having a slot therein with a narrow portion for the recep-

tion of the screw shank and an enlarged portion permitting passage of the screw head, catch means rigid with said member and disposed for engagement with said lug to interrupt falling movement of the hanger upon failure of said screw, and means rendered effective as an incident to falling movement of the catch means into engagement with the lug to prevent rotation of said member relative to said box and shifting of said screw from the narrow portion of said slot into 10 the enlarged portion thereof.

13. A hanger for an electrical fixture and for use with a conventional outlet box having a lug thereon adapted to receive a mounting screw, said hanger comprising, in combination, a fixture supporting member having an aperture therein to receive the mounting screw, and a catch rigid with said member adjacent said aperture and having a

shoulder portion spaced from and overlying said member and adapted to engage said lug upon failure of the screw, said shoulder portion being positioned in laterally offset relation to said aperture so as to permit unobstructed passage of the screw.

ARTHUR I. APPLETON.
